UNITED STATES PATENT OFFICE.

WILLIAM S. JOHNSON AND JOHN W. SHEFFER, OF BERWICK, PENNSYLVANIA, ASSIGNEES TO AMERICAN CAR AND FOUNDRY COMPANY, OF NEW YORK, N. Y., A CORPORATION OF NEW JERSEY.

ELECTRIC HEATER FOR LONG BARS.

Application filed May 15, 1922. Serial No. 561,081.

Reference is had to the accompanying drawings, which illustrate the preferred form of the invention, though it is to be understood that the invention is not limited to the exact 5 details of construction shown and described, as it is obvious that various modifications thereof within the scope of the claims will occur to persons skilled in the art.

In said drawings:

10 Fig. 1 is a broken side elevation, part being shown in section, of our improved device for heating long bars electrically;

Fig. 2 is a broken plan view, partly in section, of one-half of our device;

15 Fig. 3 is an end elevation of our device, taken at the left in Fig. 1; and

Fig. 4 is a section taken on the line 4—4 of Fig. 1.

It is an object of our invention to provide 20 an improved means for heating long bars electrically, and particularly bars to be supplied to rivet making machines. It is also an object of our invention to provide a heater of the resistance type which shall be practically 25 closed save for the openings through which the bars are inserted and withdrawn and it is also an object of our invention to provide a heater of the type described with means for preventing excessive cooling of the bar as it 30 is fed to the rivet making machine.

With these and other objects in view, our invention comprises a heating chamber carried upon suitable supports, the end supports 1 and 2 being rectangular while the intermediate supports 3 have inclined portions which meet at the center of the supports. The supports are secured to suitable foundations 4 by bolts 5 and carry I-beams 6, the I-beams being spaced from the supports by 35 suitable insulation 7. As will be seen from Fig. 4, the end I-beams 6 are carried by all of the supports while the intermediate I-beams 6 are carried by the end supports 1 and 2. Side plates 8 are secured to the ends of all the 40 supports by bolts 9. Mounted upon the I-beams 6 are slotted channel or trough-shaped sections 10 and 11 extending the greater part of the length of the beams, the sections 10 mounted upon the end beams 6 being narrower 45 than the sections 11 upon the intermediate beams and having outer flanges 12 of greater length than the inner flanges. In the sections 10 and 11 are mounted a plurality of short

strips 13, 14 and 15 of heat resisting material or fire brick having suitable insulating qualities, the strips being cemented in place and strips 14 and 15 being rectangular in shape while strip 13 is provided with an inclined upper surface having its front edge higher than its rear edge. Mounted upon the strips 14 are the continuous supports 16, formed of the same material and which serve to carry a roof or cover 17, shown as composed of a layer 18 of suitable heat resisting insulating material and a layer 19 of fire brick. The end supports 16 serve as side walls for the heated chamber while the intermediate supports 16 serve as separators and with the I-beams 6, divide the interior of the chamber into a number of separate and smaller heating sections, 70 all of which are in open communication with a drawing section in the bottom portion of the chamber. While we have shown two intermediate I-beams, it is to be understood that more or less beams may be used in accordance 75 with the capacity desired for the device. It is also to be understood that while we have shown the strips 13, 14, 15 and 16 formed separately, they may be formed in other ways to provide the ledges on the members 13 and 15 80 and the support for the roof or cover.

In brackets 20 secured to the webs of the I-beams 6 by bolts 21, rods 22 carrying bent arms 23 are rotatably mounted. The arms 23, in their normal positions, as shown in the drawings, lie between the ends of the strips 13 and 15 in the slots 23' cut in the sections 10 and 11. The rods 22 project at one end of the heating chamber through the channel end member 33 and are provided with handles 24, 90 weighted as at 25 so as to automatically return the rods 22 and arms 23 to their normal positions.

Mounted upon the projecting portion of the beams 6, at one end of the heating chamber, 95 but insulated therefrom, are guide plates 26 having guides 27 which guide the electrodes 28 in their reciprocations on the plates 26. The electrodes are operated by handles 29 having stems 30 which are connected to the 100 electrodes but insulated therefrom by insulating connections 31. The stems 30 pass through openings in guide brackets 32 mounted upon the channel end member 33 and are provided with notches 34 adapted to be 105 engaged by weighted pawls 35 to limit the in-

- ward movement of the electrodes 28. The electrodes are moved inwardly by weights 36 connected to the handles 29 by flexible connectors 37 which pass over pulleys 38 carried by the brackets 32. Current is supplied to the electrodes 28 by flexible cables 39 which are connected to any suitable source of power (not shown) and pass through slots 40 in the guide plates 26.
- 10 At the other end of the heating chamber, a plate 41 mounted on, but insulated from, the I-beams 6 supports electrodes 42 fixed in position on the plate 41 by blocks 43 and 44, of suitable insulation, and straps 45 secured to the plate 41 by bolts 46. The bolts 46, in some cases, pass through the flanges of the I-beams 6 and secure the plate 41 to the beams 6, the bolts 46 being insulated from the beams 6. Current is supplied to the electrodes 42 by 15 conductors 47 connected to the source of power. A cover 48 for the electrodes 42 is secured to the plate 41 by bolts 49 but is insulated from the plate 41.

To prevent excessive cooling of the bar as 20 the bar rests upon the bottom of the chamber before and during the time it is being fed to the rivet making machine through a discharge opening 50 in the end support 2, there is provided an inclined floor 51 of fire brick or other 25 suitable material in which there is embedded resistance grids 52 connected by conductors 53 to a suitable source of power so that the grids may be heated and the temperature of the floor raised.

- 30 In the operation of our device, rods 54 are placed upon the ledges formed by the strips 13, which constitute the heating sections, the inclination of the upper surface of the strips 13 causing the rod to roll back against the strips 15. When so positioned the rods will be in line with the corresponding electrodes 28 and 42 and the weights 36 will cause the rods to be firmly held between the electrodes. As these rods are being heated other rods are 35 placed upon the ledges formed by the strips 15. When a rod is heated to the desired temperature, the electrode 28 is withdrawn and the rod, knocked from its position in one of the heating sections by operation of the rod 40 22 and arms 23, falls to the drawing section and upon the bottom of the chamber, slots 55 being provided in the plate 26 to permit the passage of the end of the rod. The rod being engaged at a plurality of points by the arms 45 23 is not bent as it would be if it were engaged at the ends only. The rod on the strips 15 is then grasped by the operator and rolled onto the strips 13 whereupon it rolls back against the strips 15. The handle 29 is thereupon released and the weight 36 brings the electrode 28 against the rod and forces the rod against the electrode 42. At the bottom of the heating 50 chamber the rod rests upon the heated floor 51 and the rod stays in contact with the floor as it is drawn through the discharge opening 50

of the drawing section to be fed to the rivet making machine.

What we claim is:

1. In an electric heater having a heating chamber for long bars, a heating circuit 70 adapted to be completed by a bar in said chamber heated from an outside source and means in said chamber for maintaining the bar in a heated condition upon removal of the bar from the circuit.
2. In an electric heater having a heating chamber for long bars, a heating circuit 80 adapted to be completed by a bar in said chamber, independently heated means in said chamber for maintaining the bar in a heated condition upon removal from the circuit and means for moving the bar from the heating circuit to the heat maintaining means.
3. In an electric heater having a heating chamber for long bars, a heating circuit 85 adapted to be completed by a bar in said chamber, a floor for said chamber adapted to receive the bar upon removal from the circuit, electrical floor heating means embedded in said floor and means for moving the bar from 90 the heating circuit to the floor.
4. In an electric heater for long bars, supports for the bars, electrodes adapted to engage the bars to complete the heating circuits, independently heated means for maintaining 95 the bars in a heated condition upon removal from the circuits and means for moving the bars from said supports to said heat maintaining means.
5. In an electric heater for long bars, supports for the bars, electrodes adapted to engage the bars to complete the heating circuits, an electrically heated floor to receive the bars upon removal from the circuits and means for moving the bars from said supports to 100 said floor.
6. In an electric heater for long bars, a heating chamber adapted to receive the bars, supports in said chamber for the bars, electrodes adapted to engage the bars to complete 105 the heating circuits, an electrically heated floor for said chamber and arms pivotally mounted on said supports adapted to move the bars from said supports to said floor.
7. In an electric heater for long bars, a heating chamber having a cover, supports for said cover, ledges on said supports to receive the bars, electrodes adapted to engage the bars to complete the heating circuits, an electrically heated floor for said chamber and arms pivotally mounted on said supports 110 adapted to move the bars from the ledges to the floor.
8. In an electric heater for long bars, a covered heating chamber having a common discharge opening, supports for said cover adapted to receive the bars, electrodes adapted to engage the bars to complete the heating circuits, a floor for said chamber and means for moving the bars from the supports to 115
- 120
- 125
- 130

the floor, said floor being inclined to guide the bars to the common discharge opening.

9. An electric heater having a heating chamber provided with oppositely disposed heating sections for long bars, electric heating circuits adapted to be completed by bars within said heating sections, said chamber also having a drawing section in open communication with said heating sections and adapted for receiving heated bars upon removal thereof from the heating circuits.

10. An electric heater having a heating chamber provided with oppositely disposed heating sections for long bars, and an intervening bar receiving passage between said heating sections, electric heating circuits adapted to be completed by bars within said heating sections, said chamber also having a drawing section in communication with said heating sections through said passage, said drawing section adapted for receiving heated bars directed into the passage upon removal of the bars from the heating circuits.

11. An electric heater having a heating chamber provided with horizontally aligned heating sections for long bars, electric heating circuits adapted to be completed by bars within said heating sections, said chamber also having a common drawing section in open communication with said heating sections provided with a common discharge and so formed as to receive heated bars upon removal thereof from the heating circuits and to direct the bars to the common discharge.

12. An electric heater having a heating chamber provided with oppositely disposed heating sections for long bars, electric heating circuits adapted to be completed by bars within said heating sections, said chamber also having a drawing section disposed below the heating sections and in open communication with the same, said drawing section adapted for receiving heated bars upon removal thereof from the heating circuits and maintaining the bars in a heated condition.

13. An electric heater having a heating chamber provided with oppositely disposed heating sections for long bars, electric heating circuits adapted to be completed by bars within said heating sections, said chamber also having a downwardly sloped drawing section in open communication with said heating sections and adapted for receiving heated bars upon removal thereof from the heating circuits.

14. An electric heater for long bars comprising a plurality of supports, a floor mounted on said supports, supporting beams mounted on said supports, bar holding means carried by said beams, a cover supported by and extending over the bar holding means and defining with the floor a heating chamber, and electrodes positioned outside of the chamber for engaging the bars to complete the heating circuits.

15. An electric heater for long bars comprising a plurality of supports, a floor mounted on said supports, supporting beams mounted on said supports, bar holding means carried by said beams, a cover extending over the bar holding means and defining with the floor a heating chamber, supports for said cover carried by said bar holding means, said cover supports serving as separators for the bars during the heating of the latter, and electrodes positioned outside of the chamber for engaging the bars to complete the heating circuits.

16. An electric heater for long bars comprising a plurality of supports, a floor mounted on said supports, beams carried by said supports, bar holding means carried by the beams, a cover supported by the beams and extending over the bar holding means and defining with the floor a heating chamber, bar moving means carried by said beams, and electrodes outside of the heating chamber for engaging the bars to complete the heating circuits.

17. An electric heater for long bars comprising supports, a floor mounted on the supports, beams mounted on the supports, bar supporting means carried by the beams, said bar supporting means being provided with slots, a cover supported by the beams and arranged over the bar supporting means to define with the floor a heating chamber, arms pivotally secured to the beams and engaging in the slots in the bar supporting means and adapted to move the bars from the supporting means to the floor, and electrodes outside of the heating chamber for engaging the bars to complete the heating circuits.

18. In a heater for long bars, a heating chamber having a plurality of horizontally aligned bar supporting sections upon which the bars are heated, and a downwardly tapering floor beneath said bar supporting sections and forming a common drawing section for all of said bar supporting sections to direct the bars to a common discharge.

19. In a heater, a heating chamber for long bars having a plurality of horizontally aligned bar supporting sections, and a common drawing section for said bar supporting sections, said drawing section being so formed as to direct the bars to a common discharge.

20. In a heater, a heating chamber for long bars having a plurality of horizontally aligned bar supporting sections upon which the bars are heated, and inclined walls below said bar supporting sections forming a common drawing section for said bar supporting sections to receive the bars and to direct the same to a common discharge.

In witness whereof we have hereunto set our hands.

WILLIAM S. JOHNSON.
JOHN W. SHEFFER.
